UNITED STATES PATENT OFFICE

GEORGE L. MOORE, OF CHICAGO, ILLINOIS, ASSIGNOR TO ALEMITE CORPORATION, OF CHICAGO, ILLINOIS, A CORPORATION OF DELAWARE

MEASURING UNIT FOR LUBRICATING SYSTEMS

Application filed January 18, 1926. Serial No. 82,075.

My invention relates to lubricating systems by means of which a lubricant may be delivered from a central station to a plurality of remote points in measured quantities and without any possibility of delivering an excessive quantity at any point; and the object of the present invention is to produce a simple and novel measuring unit for use at a discharge or delivery point in such a system.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a vertical section through one of my improved devices and a fragment of a member containing a bearing to be lubricated; Fig. 2 is a view similar to Fig. 1, showing a different position of the movable element; and Fig. 3 is a section on line 3—3 of Fig. 1.

Referring to the drawings, 1 represents a casing adapted to be screwed or otherwise attached to a support A which contains a bearing to be lubricated. The casing contains an upper chamber 2 and a lower chamber 3 connected together by a long central cylindrical passage or bore 4. Lubricant is supplied into the upper chamber through a suitable conduit 5, and the lubricant is discharged from the device through an outlet port 6 leading out of the bottom of the lower chamber 3.

Slidable within the bore passage 4 is a shuttle-like device which, in the form shown, comprises two cylindrical end portions 7 and 8 connected by a stem 9; the parts or heads 7 and 8 having a sliding fit in said bore or passage. The length of the stem is less than the length of the bore or passage so that whenever one of the piston-like heads lies in whole or in part in said bore or passage, communication between the chambers 2 and 3 will be interrupted. Below the shuttle is a spring 10 that normally holds the same up in about the position shown in Fig.

1, with the head 7 lying within the chamber 2 above the passage, whereby the lubricant, indicated at B, may flow into the upper portion of the passage around the same. When pressure is applied to the lubricant at the central station, so as to force the lubricant toward the various measuring units of the system, the shuttle will be pressed down against the resistance of the spring so as first to interrupt communication between the upper chamber 2 and the passage 4, and then carry the lower head 8 below the lower end of the passage. As the shuttle moves down from the position shown in Fig. 1, a quantity of the lubricant is trapped between the heads and is carried down through the passage. As soon as the lower head has travelled down far enough to clear the lower end of the passage, the lubricant that has been carried along with the shuttle flows into the lower chamber 3 and from there can pass through the outlet 6 into the bearing to be lubricated. In the arrangement shown, the parts are so proportioned that the spring will be completely closed before the upper head reaches the lower end of the passage, thus preventing the shuttle from being forced completely through the passage. Where a central spring, arranged directly over the discharge outlet, is employed, there may be an auxiliary discharge outlet or passage 11 through which the lubricant may flow in the event that pressure is maintained at the source after the spring has been closed.

It will thus be seen that I have produced a measuring device that positively shuts off the main body of lubricating material before any of such material can be delivered to the discharge outlet, so that under no conditions can there be established an open passage between the upper chamber, that is, the main supply of lubricating material, and the lower chamber, which would result in the delivery of an excessive amount of lubricating material to the bearing. Viewed in one aspect, the upper end of the passage 4 may be regarded as the effective inlet of the device, and the lower end of this passage may be said to be the effective outlet of the device. Therefore it will be seen that I have provided

means for positively closing the inlet before the outlet is opened and for positively closing the outlet before the inlet is opened.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A measuring device having an inlet and an outlet, a shuttle in said device having a pocket to receive lubricant from the inlet and deliver it to the outlet, said shuttle having ends of equal cross-section, a spring tending constantly to hold said shuttle in a position in which said pocket communicates with the inlet and is out of communication with the outlet, and said shuttle being adapted to be moved by fluid pressure at the inlet to close communication between the pocket and the inlet and place said pocket in communication with the outlet.

2. A measuring device having an inlet and an outlet, a movable shuttle in said device having a pocket therein, the parts being so constructed and arranged that when the shuttle is moved in one direction it first interrupts communication between the pocket and the inlet and then opens communication between the pocket and the outlet and when it is moved in the opposite direction it first interrupts communication between the pocket and the outlet and then opens communication between the pocket and the inlet, and a spring tending constantly to move said shuttle in the second of said directions, and the shuttle being exposed to the liquid at the inlet and being adapted to be moved in the first of said directions by the liquid at the inlet when the pressure reaches a predetermined value.

3. A measuring device comprising an upper and a lower chamber connected together by a long passage of uniform cross-section, a shuttle fitting slidably in said passage, said shuttle having in the side a pocket shorter than the length of said passage, and a spring tending constantly to hold the shuttle in such a position that the pocket communicates with the upper chamber, the upper chamber having an inlet for fluid and the lower chamber having a fluid outlet, said shuttle movable in opposition to said spring responsive to increase in lubricant pressure in said upper chamber.

In testimony whereof, I sign this specification.

GEORGE L. MOORE.
